UNITED STATES PATENT OFFICE.

GEORGE GORTON, OF RACINE, WISCONSIN.

ROTARY CUTTING-OFF SAW AND THE LIKE.

1,078,193.

Specification of Letters Patent.

Patented Nov. 11, 1913.

Application filed October 25, 1912. Serial No. 727,749.

To all whom it may concern:

Be it known that I, GEORGE GORTON, a citizen of the United States, residing at Racine, in the county of Racine and State of Wisconsin, have invented certain new and useful Improvements in Rotary Cutting-Off Saws and the like, of which the following is a specification.

This invention relates to certain improvements in metal cutting-off saws of the internal type; and the objects and nature of my invention will be readily understood by those skilled in the art in the light of the following explanation of the accompanying drawings showing what I now believe to be the preferred embodiment from among other formations, arrangements and constructions within the spirit and scope of my invention.

20 This case constitutes a substitute for and a continuation in part, of my application S. No. 682,909, filed March 11, 1912, for improvements in rotary metal cutting off saws.

The invention consists in certain novel features in construction and in combinations and arrangements as more fully and particularly set forth and specified herein-after.

Referring to the accompanying drawings:—Figure 1, is a side elevation of a saw embodying my invention. Fig. 2, is a section on the line 2—2, Fig. 1. Fig. 3, is a section on the line 3—3, Fig. 1. Fig. 4, is a section on the line 4—4, Fig. 1. Figs. 5, 35 6, and 6^a, are detail views of modified formations. Fig. 7, is a detail view of a modified form wherein small high-speed cutters are inserted in the blocks.

An object of this invention is to provide 40 a metal saw or cutting off device wherein the blade, drum or cutter holder has a central work receiving opening and carries a ring consisting of a minimum number of abutting thrust sustaining elements surrounding said opening and suitably uniformly locked to the blade to be carried and driven thereby, said series of elements comprising locking wedges or equivalent elements projecting into the blade (as by fitting in radial pockets therein) and intervening blocks or the like, fitting the edge of the blade around the opening and locked by said wedges and provided with cutting points or otherwise shaped, or formed to 55 provide cutters.

In the drawings, I show a blade 1, formed

at its edge portion to be secured to a suitable rotary driving drum or hollow hub. This blade is formed with a central work receiving opening 10, and with a series of approximately radial pockets, slots or sockets 11, uniformly spaced around the central opening and at their inner ends opening thereinto. The series of thrust sustaining elements consists of several preferably similar radially arranged locking keys or wedges 2, and a like number of preferably approximately similar intervening blocks 3, forming cutters and abutting against the keys 2. The curved outer longitudinal edges 30, 70 of the blocks (cutters) longitudinally fit and conform to the curvature of the edges 12, of the blade intervening between the pockets, and the block edges 30 are preferably slightly greater in length than the edges 12, of the blade and extend from pocket to pocket. The edges 30, and 12, of the blocks and blade are preferably longitudinally and correspondingly grooved and ribbed, approximately as shown to interlock for the purpose of stiffening the blocks against lateral stresses. In the specific example illustrated, I show the edges 30, of the blocks beveled off on their side faces to form a projecting central V edge, while the edges 12, of the blade are correspondingly grooved to receive and center the same, although I do not wish to so limit my invention. The blocks 3, are also formed with opposite or front and rear transverse end edges 31, 32, usually forming approximate inward continuations of the adjacent edge walls of the pockets.

The inner longitudinal portion of each block between the end edges 31, 32 is provided or formed with an inwardly projecting cutter or working point or end 33, and usually with a cutter throat 34. The cutters (blocks 3) are locked together and to the saw blade, by driving the keys between the ends of the cutters and tightly into the pockets in the saw blade so that the projecting inner ends of the keys will be tightly wedged between the cutters and each cutter will be backed by a key tightly abutting against or backed by the front end of the next succeeding cutter in the direction of rotation of the saw blade. The longitudinal edges of the keys and edge walls of the pockets are correspondingly ribbed and grooved to interlock against lateral displacement of the keys and to properly center the

same in the plane of the saw blade. If so desired, these edges can be formed with V-shaped projecting edges and grooves. The end edges 31, 32, of the cutters 3, are also 5 similarly formed to interlock with the edges of the keys to brace and lock the abutting parts against lateral displacement.

In the example disclosed by Fig. 1, the keys taper approximately from end to end 10 and the longitudinal edges 20, thereof converge from the inner ends of the keys toward the outer ends thereof, and the longitudinal edges of the pockets 11, and the end edges 31, 32, of the cutter blocks are correspondingly inclined. The cutter blocks are preferably a very slight fraction of an inch 15 longer than the distance between the pockets. Usually the variation in length between the cutter blocks and the blade edges between 20 the pockets is not perceptible to the eye without the use of instruments, but is sufficient to place the ring of thrust sustaining elements when the keys are driven home, under greater pressure, tension or strain than the 25 pressure or tension exerted by the keys on the blade, thereby relieving the table of the excessive pressure usually necessary to properly maintain the thrust elements. The keys wedge in the pockets under sufficient pressure 30 to prevent loosening thereof and to tie the ring or thrust elements to the blade and to drive the same with the blade and to distribute the stress and strain of the cutters in action uniformly about the blade. The 35 keys most tightly lock the thrust elements together into a ring of rigid thrust receiving, sustaining and transmitting elements whereby the thrust of the cutters in action is distributed through said ring and completely 40 around the blade opening. However, possibly, one longitudinal edge only of each key might be inclined leaving the other edge straight or as shown in Fig. 5, each blade pocket might have straight parallel edges, 45 and the portion of each key tightly fitting in the same might have straight parallel edges with the outer end of the key forming the wedge and having inclined outwardly converging edges 21, to rigidly lock the ring of 50 thrust elements. The locking key arrangement might be reversed, *i. e.* the keys might be locked by inward longitudinal movement instead of outward longitudinal movement in accordance with the formation disclosed 55 by Fig. 1.

In Fig. 6, I show a formation wherein the inner end of the key 25, reduces inwardly to constitute a wedge by the formation of inclined edges 35, so that the key locks the cutter blade by inward longitudinal movement toward the axis of rotation. The keys are driven away from the pocket floors or abutments to lock the cutter blocks and are forced toward said floors to release the cutter blocks, 65 the end edges of the cutter blocks being

formed to correspond to the inner end edges of the keys to attain this result.

In the formation shown by Fig. 6^a, the same result as in the structure of Fig. 6, is attained by tapering each key 25', throughout its length, the longitudinal edges 35' of the keys converging toward the central opening of the saw, the coöperating edges of the pockets and cutter blocks being correspondingly inclined. 70

In order to maintain keys that lock by inward movement, against loosening movement in the blade, I show each key 25 or 25', formed with a longitudinal threaded socket in its heel or outer end and receiving a headed tightening screw *s*, longitudinally adjustable therein and having its head *s'*, projecting beyond the key and adapted to seat or 80 abut against the pocket floor.

Those skilled in the art will readily understand that after the cutter blocks and keys have been assembled, fitted to the blade and tightened by forcing the keys inwardly toward the axis of rotation of the saw, that the parts can be tightened to the limit and locked 90 in such positions by rotating the screws *s*, of the keys to unscrew them from the key ends, while the screw heads are seated against the pocket floors. When it is desired to remove one or more cutter blocks, the keys 95 will be first unlocked by turning the screws in a direction to screw them into said keys.

It will be observed that during operation, the thrust of the cutters in action is transmitted around the ring of abutting elements 100 and hence distributed around the table through the medium of the keys. Furthermore, should a cutter point break, the blade will be protected against injury by the body portion of the cutter and by the adjacent key. 105

Those skilled in the art will readily understand the advantages and utility of such an arrangement whereby the blade is protected and the strain and thrust of the cutters is distributed, and yet whereby cutters are rendered readily removable and renewable. 110

In the construction disclosed by Fig. 7, I show a construction wherein the blocks 3', (corresponding to blocks 3, of Fig. 1) are formed with pockets 33^a, to receive and hold pieces of tool steel or high duty or so called high speed steel to form the cutting or working points 33', of or for the blocks. These cutting points or inserted cutters 33', can be inserted and secured in the blocks in any 115 suitable manner or by any suitable means, preferably so that they can be removed therefrom when worn out to permit insertion of new or perfect cutting points, or if so desired to permit removal of the points for 120 sharpening, although it is my present intention not to remove the cutting points from the blocks for sharpening.

In the particular example illustrated by Fig. 7, the pieces of steel 33' are formed with 130

a slight taper and are driven tightly into the pockets formed in the blocks to receive the same, so as to rigidly wedge the cutting points into the blocks against accidental displacement. When the cutting points wear out or become defective, they can be knocked out and new points inserted. Even if these points are composed of high priced material, they can be made comparatively small as they are carried by the blocks, and hence the expense of discarding points after a few grindings will not be excessive.

It is evident that various changes, modifications and variations might be resorted to without departing from the spirit and scope of my invention and hence I do not wish to limit my invention to the exact disclosure hereof.

What I claim is:—

1. A saw having a central work receiving opening and a series of blocks surrounding said opening and provided with cutting points projecting thereinto and intervening keys abutting against said blocks and locking the same to said saw against lateral deflection and to rotate therewith, whereby a ring of abutting thrust sustaining elements is formed.

2. A saw having an annular series of radial uniformly spaced pockets and intervening edges, a series of blocks provided with cutting points, said blocks being fitted to the saw edges between said pockets, and keys fitting said pockets and intervening between, abutting and locking said blocks.

3. A blade having a central work receiving opening, removable uniformly spaced blocks arranged around said opening and fitted to the blade edge, said blocks provided with cutting points within said opening, and means locking said blocks to the blade.

4. A holder having a central work receiving opening and an annular series of abutting thrust sustaining elements removably locked to said holder and arranged around said opening and consisting of blocks provided with cutting points and keys intervening between and abutting against the blocks and locking the blocks to the holder.

5. A holder having a central work-receiving opening and radially arranged key sockets uniformly spaced around said opening, a series of removable blocks fitting the holder between said sockets and having cutting points in said opening, said keys fitting said sockets and intervening between, abutting and locking said blocks.

6. A blade having a central work receiving opening, a series of removable blocks arranged around said opening and fitting the blade edge and provided with inwardly projecting cutter points, and means for locking said blocks to the blade and in connection therewith forming a ring of abutting thrust sustaining elements.

7. A blade having a central work receiving opening and uniformly spaced pockets arranged around said opening, blocks provided with cutters, said blocks removably fitting the blade edge between said openings and being slightly longer than the distance between the pockets, and keys removably fitting said pockets, and interposed between and engaging said blocks and locking the same to the blade and between the keys. 70

8. A cutting off saw consisting of a blade having a central work receiving opening, and a ring of abutting thrust receiving and transmitting elements locked to the blade and arranged around said opening thereof and composed of a series of abutting cutter blocks and keys, the cutter blocks being arranged between and alternating with the keys. 75

9. A cutting off saw comprising a blade having a central work receiving opening, blocks longitudinally fitted to the curved edge of the blade around said opening and at their inner edges formed with cutters, and means for removably locking said blocks to the blade. 80

10. A saw blade having a central work receiving opening, an annular series of uniformly spaced blocks arranged in and around said opening, and means comprising blade pockets for locking said blocks in the opening and to rotation with the blade, each block formed with a cutter. 85

11. A saw blade having a central work receiving opening, a series of blocks having cutters at their inner longitudinal edges and having their outer longitudinal edges curved and formed to fit and interlock with the edge of the blade about said opening, and means spacing said blocks and locking them in operative position with respect to the blade. 90

12. A rotary saw blade, blocks having cutters at one edge and at the opposite edge removably fitted to the saw blade edge, the edges of the blade and blocks interlocking against lateral deflection, and keys interposed between said blocks and locking them together and to the blade. 95

13. A rotary saw blade having edge pockets, keys therein and projecting therefrom and provided with locking screws abutting the floors of the pockets for forcing said keys outwardly in the pockets to locking position, and cutter blocks locked to the blade by such keys. 100

14. A saw blade having spaced pockets and intervening edges, cutter blocks fitting said intervening edges between the pockets and tapering keys wedged between and engaging the ends of the blades at the exterior of said pockets and wedged in said pockets to lock the blocks to rotation with the blade. 110

15. A blade having a central work receiving opening, a series of removable blocks 115

arranged around said opening and fitting the blade edge and provided with inwardly projecting cutter points, and means for locking said blocks to the blade and in connection therewith forming a ring of abutting thrust sustaining elements, said block having pockets and inserted pieces locked therein to form said cutter points.

16. A blade having a central work receiving opening and uniformly spaced pockets arranged around said opening, blocks provided with inserted cutting points, said blocks removably fitting the blade edge be-

tween said openings and being slightly longer than the distance between the pockets, and keys removably fitting said pockets and interposed between and engaging said blocks and locking the same to the blade and between the keys.

In testimony whereof I affix my signature 20 in presence of two witnesses.

GEORGE GORTON.
